UNITED STATES PATENT OFFICE

JEAN DELATTRE-SEGUY, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS AND APPARATUS FOR TREATING OIL

Application filed June 28, 1926. Serial No. 118,980.

This invention relates to improvements in process and apparatus for treating oil, and refers more particularly to that type of construction in which the oil is distilled by the heat or radiation applied to the oil while the latter is in a relatively thin film.

The present method not only secures a very even heat transfer between the radiated heat units and the thin film of oil, but also is applied in such a way that the heat does not have to pass through the still or other material holding the oil. In the particular application of the invention, I shall describe it as applied to the distillation of oil approximately at atmospheric pressure, although it is to be understood that the invention is in no way limited to such method of distillation.

Referring to the drawings, Fig. 1 is a vertical sectional view taken through the line B—B of Fig. 2. Fig. 2 is a transverse sectional view taken through the line A—A of Fig. 1. Fig. 3 is a plan view with parts shown in dotted lines.

Referring to the drawings, 1 designates a furnace setting which may be of brick, provided with the combustion chamber 2, burner 3, flue 4 leading to combustion chamber 5 having flue outlet 6 leading to stack 7. The lower side of the combustion chamber 5 may take the form of a brick wall 8, or it may take the form of a metal plate, if desired.

The arrangement is such that the heat radiates through the wall 8 into the heating chamber 9 below. In the chamber 9 on suitable supports 10 and 11, is mounted an inclined plate 12, which plate 12 has the flat base portion 13 and side members 14, the arrangement being such as to form a shallow wide channel for the oil. The ends of the plates are mounted on adjustable jacks 15, the arrangement being such that the slope of the plate 12 may be varied so as to insure of a more rapid or slow passage of the oil film thereacross. This will of course, permit of regulating the time of reaction. The oil is introduced to the upper end of the plate through the pipe 16 by means of a transversely extending perforated nozzle 17. The oil residue is drawn off the plate through the transversely extending funnel 18 provided

with drawoff pipe 19 leading to any suitable residue storage. The vapors generated, pass up out of the chamber 9 into the vapor collector 20 and thence to vapor pipe 21 leading to any suitable condenser and receiver, not shown, or the vapors may be carried away to some other place for further treatment while still in vapor form.

Inasmuch as the temperature of the combustion chamber 5 is very intense, it may be desirable to cool the upper wall of the chamber by air flues 22, or in any other suitable manner. The air thus preheated, may be used if desired, in the combustion of the fuel.

From the foregoing, it will be seen that the carbon deposited on the inclined plate, will not interfere with the reaction because the heat instead of having to pass through the bottom of the plate and thence through the non-conductive carbon film or deposit, comes down directly on top of the oil through the open space in the chamber 9.

In carrying out the process of cracking petroleum oil at atmospheric pressure, the oil, as for example fuel oil, may be passed slowly from the plate and subjected to the relatively intense heat of radiation at whatever temperature desired, say from 900 to 1200° F. more or less, which will break down a substantial part of the fuel oil into light constituents such as gasoline or the like. Other constituents form, such as kerosene or gas oil, which can be later separated out from the pressure distillate, or all of the constituents may be subjected to further cracking elsewhere, if desired.

The carbon deposited upon the plate during the cracking operation, may from time to time be scraped off, by suitable scrapers, not shown.

I claim as my invention:

1. A process for distilling hydrocarbon oils which comprises continuously flowing the oil by gravity in a relatively thin film over an unheated inclined surface, applying a distilling heat solely to the upper surface of said film without heating the film from below, and removing and condensing the evolved vapors.

2. A process for distilling hydrocarbon

oils which comprises continuously flowing the oil by gravity in a relatively thin film over an unheated inclined surface, applying a distilling heat solely to the upper surface of said film without heating the film from below, said distilling heat being transmitted to the film by radiation from a heating surface spaced away from the upper surface of the film whereby the film at no time contacts with the heating surface, and removing and condensing the evolved vapors.

3. An apparatus for distilling hydrocarbon oils comprising a closed distillation chamber having a heat radiating top portion, an unheated inclined plate disposed within said chamber below said heat radiating top portion, means for introducing oil to said chamber adjacent the higher end of said inclined plate to flow over the plate in a thin film, means for applying a distilling heat solely to said heat radiating top portion to be transmitted to the oil flowing over said plate, and means for removing vapors from said chamber.
4. An apparatus for distilling hydrocarbon oils comprising a closed distillation chamber having a heat radiating top portion, an unheated inclined plate disposed within said chamber below said heat radiating top portion, means for introducing oil to said chamber adjacent the higher end of said inclined plate to flow over the plate in a thin film, means for applying a distilling heat solely to said heat radiating top portion to be transmitted to the oil flowing over said plate, means for varying the inclination of said plate, and means for removing vapors from said chamber.

JEAN DELATTRE-SEGUY.
